ATTORNEYS.

UNITED STATES PATENT OFFICE.

EZRA READ GOODRIDGE, OF NEW YORK, N. Y.

DESIGN FOR A TERMINAL MEMBER FOR EXERCISING-MACHINES.

SPECIFICATION forming part of Design No. 30,972, dated June 6, 1899.

Application filed February 16, 1899. Serial No. 705,728. Term of patent 7 years.

To all whom it may concern:

Be it known that I, EZRA READ GOODRIDGE, a citizen of the United States, residing in the city of New York, borough of Manhattan, in the county and State of New York, have invented and produced a new and original Design for a Terminal Member for Exercising-Machines, of which the following is a specification, reference being had to the accompanying drawing, forming a part thereof, in which is represented a perspective view of a terminal member embodying the features of my design.

The design consists of a ring figure over which a cord is apparently passed and secured

in loop form. The representation of the cord presents two parallel members that extend over the ring figure, connected by a transverse loop crossing both of the parallel members, the two members and loop appearing as formed from a single piece of material and all the parts appearing as integral. 20

I claim—

The design for a terminal member for exercising-machines herein shown and described. 25

EZRA READ GOODRIDGE.
